REFRIGERATOR CABINET CONSTRUCTION

John Crawford Moore, Connersville, Ind., assignor, by mesne assignments, to Reconstruction Finance Corporation, Chicago, Ill., a corporation of the United States

Application March 17, 1938, Serial No. 196,568

4 Claims. (Cl. 220—9)

This invention relates to refrigerator cabinet construction and has in view the provision of co-acting interlocking structural members in a refrigerator body or cabinet which permit elimination of woodwork and enable the refrigerator body or cabinet to be made substantially entirely of steel yet strong and relatively light in weight and without sacrificing thermal insulating efficiency. The structure for accomplishing these results has also been devised with a view towards providing a more effective and permanent seal around the door opening, ability to cushion shocks incident to door closing, reduction and simplification of parts, speeding up the assembling operation and improving the body construction generally.

In the drawing:

Fig. 1 is a view in front elevation of a refrigerator cabinet constructed in accordance with the features of the invention;

Fig. 2 is a horizontal section taken substantially on the line 2—2, Fig. 1;

Fig. 3 is an enlarged fragmentary horizontal section taken through the door jamb and a portion of the door, the latter being shown closed;

Fig. 4 is an enlarged fragmentary view in elevation of the casing frame structure which connects the inner and outer walls of the cabinet at the door jamb.

The cabinet or refrigerator body is generally indicated at C and the door at D. The cabinet is of all-steel construction having an inner wall or liner 5 which defines the food compartment F and an outer wall or shell 6. In the example shown, the outer shell is made up of side and back panels which are joined to provide a continuous outer wall structure, and when assembled in conjunction with the liner 5, insulation material 7 is inserted between the inner and outer walls. The side panels may be extended to rest on a suitable foundation and to provide a machinery compartment which is closed by a door 8.

The door D consists of outer shell 9 and inner pan or shell 10 which are connected in a manner to be described.

The features of the present invention are primarily concerned with a casing frame structure made up of frame member 11, which may consist of a strip of suitably shaped sheet metal, extruded or cast aluminum, or like structural shape, said strip bordering the door opening and being formed with a slightly inturned flange 11a along its one edge and at its opposite edge with a substantial right-angle flange 11b. The adjacent or

contiguous wall of the liner 5 is formed with a door jamb bead 12 terminating in a flanged edge portion 13, which substantially parallels the adjacent flanged edge portion 11b of the frame member 11 and has in effect an interlocking connection therewith. The outer shell around the door opening is provided with an inturned flange 14 which overlaps the adjacent flange 11a of the frame member 11 and is connected thereto by suitable means such as screws 15.

The food compartment or liner 5 is detachably mounted in the refrigerator body through the medium of clips or brackets 16, which may if desired be full length strips, said clips being secured to the frame strip 11 by suitable means such as screws 11 and holding the flanged edges 13 and 11b in interlocked relation.

To insure an efficient thermal break, or minimize the chances of passage of heat into the cabinet, a resilient gasket strip 18 is located between the flanges 11a and 14 of the frame member 11 and outer shell 6 respectively, and another strip 19 between the flanges 11b and 13 at the inner edge of the frame member and the adjacent or contiguous edge of the liner 5. These gaskets are preferably comprised of non-hygroscopic material having a low coefficient of heat conductivity and constructed so that they overlap the edges or flanges 11a and 11b and completely separate as well as cushion all metal parts, or hold such parts in thermally-insulated, spaced relation. Another thermal break or insulating gasket 20 is inserted over the edge of each of the clips 16.

A breaker strip 21 may then be mounted in place and secured to the frame member 11 by suitable means such as screws 22, each having a spacer 23 thereon.

The door D is also constructed so that it may be of the all-steel type, the edge of the outer shell or wall 9 being formed with an inturned flat portion 23 terminating in an angular flange portion 23a, which portions overlap similarly shaped portions 24 and 24a formed on the adjacent or contiguous edge of the door pan 10. These parts when brought together in assembled relation are provided with a thermal break or strip of insulating material 25 therebetween, the outer edge of which is constructed to form a door seal or sealing bead 25a. This combined thermal break and sealing bead or gasket 25—25a is locked in place between the outer wall 9 and inner wall or door pan 10 when the latter parts are secured to one another by suitable means such as screws 26. As a further assurance against heat passage or leakage, the thermal break or gasket 25 has its

inner edge returned over the adjacent edge of the flange 23a, as indicated at 27, and the screw heads are covered by a flap or cover strip 28.

As will be understood, the insulation strip 25 is also preferably formed of suitable non-hygrosopic material having a low coefficient of heat conductivity.

From the foregoing it will be seen that the refrigerator cabinet with the exception, of course, of the insulation and gasket material, may be readily constructed of pressed sheet metal shapes which are held in well-supported, spaced, thermally-insulated and cushioned relation. The parts may be assembled and secured in place with relative ease and expedition, the liner 5 being removable at any time desired simply by removing the clips 16. The combined thermal break and sealing strip 25-25a also facilitates assembly and resists loosening and displacement as well as subsequent breaking down of the sealing bead.

It will be understood that certain changes in structure and design of the respective parts and their arrangement and method of assembling may be made without departing from the realm or scope of the invention as defined by the appended claims.

I claim:

1. In a refrigerator cabinet, spaced outer and inner walls terminating in spaced peripheral flanges about a door opening, the flange of the outer wall extending inwardly at an angle thereto and the flange of the inner wall extending outwardly and having a substantially right angular bend therein, a casing frame of relatively thin sheet-like material interposed between said flanges and having its inner marginal edge formed with a right angular bend complementary to the bend of the flange of the inner cabinet wall and disposed in rear of the latter, and means anchoring said casing frame to said flanges including a member connected to the casing frame and accessible exteriorly of the latter and having a portion overlying the flange of the inner wall and in clamping engagement therewith to thereby draw the inner marginal edge of the casing frame and the flange of the inner cabinet wall together in interlocking relation.
2. In a refrigerator cabinet, spaced outer and inner walls terminating in spaced peripheral flanges about a door opening, the flange of the outer wall extending inwardly at an angle thereto and the flange of the inner wall extending outwardly and having a substantially right angular bend therein, a casing frame of relatively thin sheet-like material interposed between said flanges and having its opposite marginal edges disposed in rear of said flanges and in overlapping relation thereto, the inner marginal edge of the casing frame having a right angular bend complementary to the bend of the flange of the inner cabinet wall, and means anchoring said casing frame to said flanges including a mem-

ber connected to the outer face of the casing frame and having a portion overlying the flange of the inner wall and in clamping engagement therewith to thereby draw the inner marginal edge of the casing frame and the flange of the inner cabinet wall together in interlocked relation.

3. In a refrigerator cabinet, spaced outer and inner walls terminating in spaced peripheral flanges about a door opening, the flange of the outer wall extending inwardly at an angle thereto and the flange of the inner wall extending outwardly and having a right-angular outwardly facing bend therein, a casing frame of sheet-like material interposed between said flanges and disposed in the rear of the latter and in overlapping relation thereto, the inner edge of said casing frame having a right-angular bend complementary to the bend of the flange of the inner cabinet wall, means securing the outer edge of the casing frame to the flange of the outer wall, and means connecting the inner edge of said casing frame to the flange of the inner wall including clips of resilient material each having a portion secured to the outer face of the casing frame and an inwardly extending portion in clamping engagement with the flange of the inner wall to thereby draw the inner marginal edge of the casing frame and the flange of the inner wall together in interlocked relation.

4. In a refrigerator cabinet, spaced outer and inner walls terminating in spaced peripheral flanges about a door opening, the flange of the outer wall extending inwardly at an angle thereto and the flange of the inner wall extending outwardly and having a substantially right angular outwardly facing bend therein, a casing frame in the form of an elongated strip of resilient sheet material interposed between said flanges and having opposite marginal edge portions disposed in rear of said flanges and in overlapping relation thereto, the inner edge of said casing frame having a right angular bend complementary to the bend of the flange of the inner cabinet wall, strips of gasket material having a low coefficient of heat conductivity separating the respective flanged edges of the casing frame and outer and inner cabinet walls, means securing the outer edge of the casing frame to the flange of the outer wall, and means connecting the inner marginal edge of said casing frame to the flange of the inner wall including clips of resilient material each having a portion secured to the outer face of the casing frame and an inwardly extending clamping portion overlying the flange of the inner wall to thereby draw the inner marginal edge of the casing frame and the flange of the inner wall in interlocked relation, and a breaker strip detachably connected to said casing frame and overlying the latter and the peripheral edges of said outer and inner walls.

JOHN CRAWFORD MOORE.
